UNITED STATES PATENT OFFICE.

DAVID BUEL, OF COLUMBUS, OHIO.

CHAIN-LINK FOR MINING-MACHINES.

No. 894,184.

Specification of Letters Patent. Patented July 28, 1908.

Application filed December 9, 1905, Serial No. 291,058. Renewed December 19, 1907. Serial No. 407,215.

To all whom it may concern:

Be it known that I, DAVID BUEL, residing at Columbus, in the county of Franklin and State of Ohio, have invented a certain new 5 and useful Improvement in Chain-Links for Mining-Machines, of which the following is a full, clear, and exact description, reference being had to the accompanying drawings.

My invention relates to mining machines 10 and more particularly to the bit-carrying chains which are employed in such machines for the cutting of coal or other relatively soft mineral deposits.

The object of my invention is to improve 15 and strengthen the construction of such links, and to provide an improved bearing for the cutter bits whereby the efficiency is greatly increased.

Generally speaking, the invention may be 20 defined as consisting of the processes of producing such links and the combinations of elements embodied in the claims hereto annexed.

Referring to the drawings:—Figure 1 represents a side elevation of a portion of a mining chain embodying my invention, some of the links being broken out at the center; Fig. 2 represents an end elevation of the device shown in Fig. 1, the links broken therefrom being also omitted from the figure; Fig. 3 represents an enlarged perspective view of a chain block constructed in accordance with my invention; and Figs. 4 and 5 represent sectional details of said block.

35 In the drawings, 1 represents the chain, said chain consisting of side plates 2 and blocks 3, said plates and blocks being preferably formed of steel. The chain is shown in a horizontal position and, for convenience of 40 description, the parts will be referred to as if the chain were operated in such position, although it will be apparent that it may be operated in various positions. Each block is provided with a pair of eyes 4, for the reception 45 of bosses 5, projecting inwardly from the side plates. These bosses have such an exterior diameter that they fit within the eyes and form a bearing therewith and are themselves provided with a bore 6 for the reception 50 of a rivet 7, whereby they are held in operative relation to the block. Each block

is provided with a projection 8 extending upwardly therefrom. This projection, in the case of the great majority of the blocks, is inclined from the vertical, the amount of such 55 inclination varying with the different blocks, whereby the upper edges 9 of the cutter bits 10 overlap one another successively, as will appear more particularly from Fig. 2, enabling the chain to make a wide cut in the 60 material being mined. Mining chains of this general construction are old in the art, but are universally made of cast metal. In producing the blocks of my chain, I first form a blank from a drop forging, said blank being 65 similar to the block shown in the drawings, but without eyes or aperture therein. The eyes are then formed in said blank by means of a suitable drill.

The aperture 11 for the shank of the cutter 70 bit is formed as follows:—I first drill the block from top to bottom thereof and in the direction of the inclination to be given the shank of the cutter bit, thereby producing a cylindrical bore the diameter of which is 75 greater than the width of the shorter face of the shank of the bit and less than the width of the longer face of the same, said shank being preferably substantially rectangular in section. I then broach the cylindrical 80 bore, thereby providing an aperture therein that is substantially rectangular in section, with curved recesses 12 in the longer faces of said aperture, intermediate of the corners thereof. The aperture thus produced is only 85 sufficiently larger than the shank of the cutter bit to permit the same to be freely inserted and withdrawn from the same. For clearness of illustration, however, the space between the wall 13 of said aperture and the 90 forward face of the cutter bit is exaggerated. The bit is held in any desired position within the aperture, as by means of a set screw 14.

By my method of forming the aperture from the cutter bit, I am not only enabled to 95 produce the same in an economical manner, but to form a firm seat for the shank of the bit within the aperture. The corners of the aperture are squared or angular to conform to the corners of the bit shank. It frequently 100 happens, however, in the old construction, that the wider faces of the bit shank will be

rounded or irregular; and, in such case, the rounded or irregular portions will engage the sides of the aperture and will prevent the corners of the shank from fitting snugly into the corners of the aperture. This will result in more or less rotation of the bit around the axis of its shank, tending to throw the cutting edge of the same out of proper relation to the cutting edges of the adjacent bits and 10 also causing distortion of the aperture. It will also tend to loosen the set screws, and thereby cause the bits themselves to drop out of their links and become lost in the mineral, where they frequently break the machinery 15 when the mineral is being screened. By my construction, the corners of the shank are forced firmly into the corners of the aperture by the set screw, the curved recesses 12 accommodating any irregularities or projections 20 on the side faces of the shank, with the result that the bit will be held firmly in proper operative relation to the adjacent bit and without the tendency to rotate and distort the aperture that is present in prior devices 25 of this kind, and without tendency to loosen the set screw.

In order to facilitate the proper application of the drill to the block in forming the preliminary or cylindrical bore therethrough, 30 for the bit, I provide the upper or outer end of the block with a flattened face 15 which is normal to the direction of the proposed aperture. It is then only necessary to apply the drill in a direction normal to the surface 15 35 to insure the aperture being given the proper direction.

By the process and construction hereinbefore described, I am enabled to produce mining chains which are not only stronger 40 than those now in use, but which will firmly maintain the bits in proper relation to one another for operating upon the coal or other material being mined.

While I have shown, in the embodiment of 45 my invention herein disclosed, a bit shank that is substantially rectangular in section and a correspondingly shaped aperture therefor, I do not propose to be limited to such shape except as such limitation may be positively included in the claims hereto annexed or may be rendered necessary by the prior state of the art.

Having thus described my invention what I claim as new and desire to secure by Letters-Patent is:—

1. The process of making links for mining machine chains which consists in forging a blank, forming in said blank an angular aperture for the shank of a cutter bit, and providing a longitudinal recess in one or more of the faces of said aperture, substantially as specified.

2. The process of making links for mining machine chains which consists in forging a blank, forming in said blank an angular aperture for the shank of a cutter bit, and providing said aperture with one or more longitudinal recesses, substantially as specified. 65

3. The process of making links for mining machine chains which consists in forging the 70 metal into a blank having its outer face perpendicular to the direction of the proposed aperture, then drilling a hole perpendicular to said face of greater diameter than the width of the shank of the bit, and then 75 broaching out the hole to form an aperture with one or more angular corners, substantially as specified.

4. The process of making links for mining machine chains which consists in forging the 80 metal into a blank, drilling a circular hole in said blank of a diameter greater than the width of the tool or bit, and broaching out the said hole at diametrically opposite portions so as to form an aperture with one or 85 more angular corners and intermediate longitudinal recesses, substantially as specified.

5. A link for mining machine chains comprising a forged block having eyes bored therein for the application thereto of the side 90 plates, said block having an extension provided with an aperture for the reception of the cutter bit, said aperture having one or more angular corners and one or more longitudinal recesses therein, substantially as 95 specified.

6. A link for mining machine chains comprising a body having an aperture therein for the shank of a cutter bit, said aperture being oblong in cross section, one or more of the longer faces of said aperture being provided with a recess extending longitudinally of the aperture, substantially as specified. 100

7. A link for mining machine chains comprising a body having an aperture therein for 105 the reception of the shank of a cutter bit, said aperture having one or more angular corners and one or more longitudinal recesses, substantially as specified.

8. A link for mining machine chains comprising a body having an aperture therein for the reception of the shank of a cutter bit, said aperture being provided with one or more longitudinally extending recesses intermediate of the ends, the outer face of said body being normal to the axis of said aperture, substantially as specified. 110

9. A link for mining machine chains comprising a body having an aperture therein for the reception of the shank of a cutter bit, 115 said aperture having one or more longitudinal recesses therein, substantially as specified.

10. A link for mining machine chains, comprising a forged body having an aperture for

the reception of the shank of a cutter bit, said aperture having one or more longitudinal recesses therein, substantially as specified.

11. The process of making links for mining machine chains which consists in producing a blank with a circular bore and broaching out opposite portions of the bore, the width of the recesses formed by so broaching the opposite portions of the bore being less than

the diameter of said bore, thereby providing longitudinal recesses in said bore, substantially as specified.

In testimony whereof I affix my signature in the presence of two witnesses.

DAVID BUEL.
